UNITED STATES PATENT OFFICE.

RAYMOND C. PHELPS, OF LOS ANGELES, CALIFORNIA.

CONCRETE-FLOOR FORM.

Application filed January 2, 1924. Serial No. 683,927.

To all whom it may concern:

Be it known that I, RAYMOND C. PHELPS, a citizen of the United States, residing in the city of Los Angeles, in the county of Los Angeles and State of California, have invented a new and useful Improvement in Concrete-Floor Forms, of which the following is a specification.

My invention relates to improvements in forms for concrete floors and the like wherein form pans are arranged to be mounted upon a supporting structure as a mold for laying the floor and joist and are adapted to be removed without the supporting structure.

The primary object of my invention is to provide an improved form for concrete floors.

Another object is to provide an improved form adapted to facilitate the removal of form pans without disturbing the supporting structure upon which the forms and floor are laid.

A further object is to provide an improved device of the character described adapted to facilitate the initial placing of the form pans.

A still further object is to provide a device adapted to reduce the amount of lumber and labor necessary for building a supporting structure, and to reduce the labor and waste of lumber in dismantling such structure after the floor has been completed.

I accomplish these and other objects by means of the device disclosed in the drawings forming a part of the present specification wherein like characters of reference are used to designate similar parts throughout said specification and drawings and in which,

Fig. 1 is a broken plan view of my improved floor form showing the manner in which the floor is laid thereon.

Fig. 2 is a broken transverse section of a section of floor as applied upon my improved floor form.

Fig. 3 is a broken longitudinal section of a section of floor as applied upon my floor form.

Fig. 4 is a perspective view of a form pan.

Fig. 5 is a sectional detail showing the preferred manner in which the pans are secured to the supporting structure.

Fig. 6 is a longitudinal section similar to

that shown in Fig. 3 with the form pans removed.

In laying concrete floors the common practice heretofore has been to build a supporting structure consisting of a plurality of supporting beams arranged transversely to the joist of the floor to be formed, said beams being supported upon uprights. Above the beams is built a superstructure consisting of a plurality of beams running with floor joist and supported upon uprights carried by the lower beams. Form pans having side portions are secured directly to the sides of the beams by means of special nails, the side portions being nailed to the adjacent sides of adjacent beams so that the pans span the spaces between beams. The floor joist are defined by the side portions of the pans and the upper surfaces of the beams, the concrete being poured directly onto the top of the beams, and over the pans to obtain the desired thickness of floor. The concrete is allowed to set for a period of about four days after which the nails are drawn and the pans loosened and removed from under the floor, the supporting structure being left standing for a period of about three weeks to permit the thorough hardening of the concrete.

The present practice above outlined is objectionable because of the excessive quantity of lumber necessary to construct the supporting structure due to the use of both transverse and longitudinal beams, and also because of the amount of labor required to build such structure. An excessive amount of labor is also required to place the pans as workmen must operate both from above and below the supporting structure in order to place and secure the pans in position. Excessive labor is also required in removing the pans as the nails must each be drawn independently and the longitudinal beams interfere with the loosening of the pans from the concrete. The dismantling of the superstructure also requires a considerable amount of labor, and as the concrete is placed in direct contact with the upper surfaces of the longitudinal beams to which the concrete sticks more tightly than to metal the separation of the beams from the concrete requires excessive labor and frequently results in damaging the beams to such an extent as to render them unfit for further use.

To overcome these objections and to effect economy in the building of concrete floors I have devised my improved floor form which, by referring to the drawings, will be seen to consist essentially of a plurality of form pans 1 formed from suitable sheet metal and provided with downwardly bent side portions 2 and 3 formed by bending the longitudinal edges of a sheet of metal to positions diverging slightly from perpendicular relation to the body of the sheet. The side portions 3 of each pan 1 is further bent to form an outwardly disposed lateral extension 4 substantially parallel to the body 15 of the sheet. A flange 6 is formed along the outer edge of the lateral portion 4 by upwardly bending the edge of the side portion 2 of an adjacent pan 1 for a purpose hereinafter more fully explained.

20 The form pans 1 are mounted upon a suitable supporting structure consisting of a plurality of supporting beams 7 carried upon suitable upright supports 8. The beams 7 are spaced apart a distance slightly 25 greater than the length of the pans 1. Blocks 9, or other suitable supporting elements, are secured upon the sides of the beams 7 to engage and support the ends of the form pans 1, the ends of the pans being 30 held clear of the sides of the beams 7 to permit the removal of the pans without disturbing the supporting structure as hereinafter explained.

Auxiliary pans 11 are supported directly 35 above the beams 7, said pans 11 being of the same cross section as the form pans 1, but of a width only slightly greater than the width of the beams 7 so as to lap slightly onto the adjacent ends of the form pans 1 40 as best shown in Fig. 3 of the drawings.

In constructing my improved floor form, the supporting structure is first built, the beams 7 being leveled to give the desired depth of floor and floor joist in any convenient manner, said beams being regularly spaced at a distance slightly greater than the length of the pans 1, as above explained. The blocks 9 are then nailed or otherwise secured upon the sides of the beams 7 at 45 the points where the floor joist are to be found. The pans 1 are placed upon the supporting structure with the ends of the laterally disposed portions 4 of the pans resting upon and supported by the blocks 50 9, and the flange 6 of each pan interlapping the edge of the side portion 2 of an adjacent pan 1 as best shown in Fig. 2 of the drawings. The auxiliary pans 11 are then placed directly over the beams, the edges of the 55 pans 11 lapsing above the adjacent edges of the pans 1 thereby spanning the space between the ends of said pans 1. In order to hold the pans securely in place, apertures 12 are formed adjacent the edges of the 60 laterally disposed portions 4 of the pans 1 65

directly over the blocks 9. Corresponding apertures 13 are formed in the auxiliary pans 11 to register with the apertures 12 whereby the lapping edges may be secured to the blocks 9 by means of a single nail 70 or other securing element 14.

When the pans 1 and 11 have been placed upon the supporting structure as above explained the interlapping side portions of the pans form depressions defining the joist for the concrete floor. A suitable concrete mixture is then applied over the form to fill the depressions and form concrete floor joist 17 and entirely cover the form with a desired thickness of concrete floor 18 the side portion 2 of one pan being held firmly against the flange 6 of the adjacent pan by the weight of the concrete. Reinforcing bars 16 are commonly placed in spaced relation within the depressions in the form to be embedded within the concrete when poured thereby strengthening the floor joist. Apertures 15 are formed in the tops of the pans 1 to admit wires, not shown, by which ceiling material may later be secured to the 90 under side of the floor.

After the concrete has been allowed to set for a period of four days, as in the present practice, the form pans are removed and may be used in the structure of successive floors. In my improved floor form this is accomplished by removing the blocks 9 from the sides of the beams 7 which in the arrangement shown in the drawings, is readily accomplished by prying off the blocks, said blocks at the same time being moved out of engagement with the securing element 14. The form pans 1 may now be pried loose from the concrete without disturbing the beams 7 and supporting structure, as the ends of the pans 1 clear the sides of the beams. The supporting structure is allowed to stand for about three weeks as in the present practice, the auxiliary pans 11 being allowed to remain in position until the supporting frame is dismantled at which time the pans are loosened from the concrete and preserved for future use. The pans are sprayed with oil prior to the pouring of the concrete to prevent the concrete from sticking to the pans, thereby permitting the metal pans to be separated easily from the hardened concrete.

It will be noted that in my improved floor form the supporting structure consists only of a single series of supporting beams 7 which are arranged transversely to the joist, and that the concrete does not come in direct contact with any portion of the supporting structure but is molded entirely within the metal form pans 1 and 11. These points are of particular importance because of the fact that in this manner I am able to eliminate the superstructure and longitudinal beams used in common prac-

tice, thereby effecting a substantial saving both in material and labor. As explained above, the metal is readily loosened from the concrete, but the wooden beams cannot be so readily loosened and I am able to avoid the labor and loss of material. The supporting elements 9 may be pried loose and the securing means therefor removed with much less labor than is involved in the drawing of the plurality of nails commonly used. Furthermore, the initial placing of the form pans may be accomplished with much greater economy of time and labor than the pans now in common usage, as workmen may accomplish the entire placing and securing from above without any assistance from below the form.

Another point of particular importance is that the lateral extension 4 may be designed to give any required width to the floor joist 17. In general practice, a width of four and a half inches for the joist is commonly accepted as being most efficient both as to strength and fireproofing properties. In common practice heretofore, however, the width of base has been limited to the width of lumber available for the longitudinal supporting beams used. Lumber of this type comes only in certain standard sizes and in common practice either a four inch timber must be used with a corresponding width of joist, or the thickness must be increased at almost prohibitive cost by securing cleats upon the sides of the supporting beams.

While I have illustrated only the preferred embodiment of my invention it is understood that various modifications as to form and arrangement may be made without departing from the spirit of my invention and I therefore desire to avail myself of all such modifications as may fall within the scope of the appended claims.

Having thus described my invention what I claim as new and desire to secure by Letters Patent is—

1. A concrete floor form comprising the combination with a supporting structure consisting of a plurality of spaced transverse supporting beams, of a plurality of form pans having interlapping longitudinal edges forming depressions defining floor joist; supporting elements detachably connected to the supporting structure to engage and support the ends of the pans clear of the edges of the supporting beams whereby the pans may be removed without disturbing the supporting structure; and auxiliary pans supported above the beams and spanning the space between the adjacent ends of the form pans.

2. A concrete floor form comprising the combination with a supporting structure consisting of a plurality of spaced transverse supporting beams, of a plurality of form

pans having interlapping longitudinal edges forming depressions defining floor joist; supporting elements detachably connected to the supporting structure to engage and support the ends of the pans clear of the edges of the supporting beams whereby the pans may be removed without disturbing the supporting structure; auxiliary pans supported above the beams, said pans lapping the adjacent ends of the form pans; and means for securing the overlapping edges of the auxiliary pans and the form pans to the supporting members.

3. A concrete floor form comprising the combination with a supporting structure consisting of a plurality of spaced supporting beams, of a plurality of form pans having downwardly turned longitudinal edges one of which is provided with a laterally extending portion arranged to engage the opposite edge of an adjacent pan to hold said edges in interlapping relation to define joist extending transversely to the supporting beams; supporting elements detachably secured upon the supporting structure to engage and support the ends of the pans clear of the sides of the supporting beams whereby the pans may be removed without disturbing the supporting structure; and auxiliary pans supported above the beams, said auxiliary pans being shaped to conform to the form pans and to lap the adjacent ends of said form pans.

4. A concrete floor form comprising the combination with a supporting structure consisting of a plurality of spaced supporting beams, of a plurality of form pans of a length slightly less than the space between supporting beams, said pans having downwardly turned longitudinal edges adapted to interlap to define floor joist arranged transversely to the supporting beams; blocks removably secured upon the sides of the beams to engage and support the ends of the form pans clear of the sides of said beams, whereby said pans may be removed without disturbing the supporting structure; and auxiliary pans shaped to conform to the shape of the form pans and arranged to extend across the supporting beams to lap the adjacent ends of the form pans.

5. A concrete floor form comprising the combination with a supporting structure consisting of a plurality of spaced supporting beams, of a plurality of form pans of a length slightly less than the space between supporting beams, said pans having downwardly turned longitudinal edges adapted to interlap to define floor joist arranged transversely to the supporting beams; blocks removably secured upon the sides of the beams to engage and support the ends of the form pans clear of the sides of said beams, whereby said pans may be removed without disturbing the supporting struc-

ture; and auxiliary pans shaped to conform to the shape of the form pans and arranged to extend across the supporting beams to lap the adjacent ends of the form pans; and means for securing the lapping edges of the form pans and the auxiliary pans to the supporting blocks.

6. A concrete floor form comprising the combination with a supporting frame consisting of a plurality of spaced supporting beams, of a plurality of form pans of a length slightly less than the space between supporting beams, said pans having downwardly turned longitudinal edges one of which is provided with a flanged laterally extending portion adapted to interlap with the edge of an adjacent pan to define joist arranged transversely to the supporting beams; blocks removably secured upon the sides of the supporting beams to engage and support the ends of the interlapping edges clear of the sides of the beams whereby the pans may be removed without disturbing the supporting structure; and auxiliary pans supported above the beams, said auxiliary pans being shaped to conform to the shape of the form pans and being arranged to extend across the beams and lap the adjacent edges of the form pans.

30 7. A concrete floor form comprising the combination with a supporting structure consisting of a plurality of spaced supporting beams, of a plurality of form pans of a length slightly less than the space between supporting beams, said pans having their edges downwardly turned to form slightly flaring side portions; a laterally extending portion formed upon the lower edge of one of the side portions; an upwardly turned flange formed upon the edge of said laterally extending portion to interlap the lower edge of the side portion of an adjacent form pan whereby the side portions of adjacent pans are held in spaced relation to define floor joist arranged transversely to the supporting beams; blocks secured upon the sides of the beams to receive and support the ends of the laterally disposed portions whereby the form pans are supported clear of the sides of the beams to permit the removal of said pans without disturbing the supporting structure; and auxiliary pans supported above the beams and lapping the adjacent edges of the form pans.

55 8. A concrete floor comprising the combination with a supporting structure consisting of a plurality of spaced supporting beams, of a plurality of form pans of a length slightly less

than the space between supporting beams, said pans having their edges downwardly turned to form side portions; a laterally extending portion formed upon the edge of one of the side portions of each pan, each laterally extending portion being flanged to interlap with the side portion of an adjacent form pan to define floor joist arranged transversely to the supporting beams; blocks secured upon the sides of the beams to receive and support the ends of the laterally disposed portions whereby the form pans are supported clear of the beams to permit the removal of said pans without disturbing the supporting structure; and auxiliary pans supported above the beams and lapping the adjacent ends of the form pans, said auxiliary pans being shaped to conform to the form pans and having apertures adjacent the edges thereof to register with apertures formed adjacent the edges of the laterally disposed portion of the form pans whereby the lapping edges may be fastened to the supporting blocks by a common securing element.

9. In a concrete floor form, a form pan consisting of a metal sheet having the longitudinal edges thereof bent to form side portions one of said side portions being further bent to form an outwardly extending lateral extension adapted to engage the adjacent side portion of an adjacent form pan to form a mold for floor joist.

10. In a concrete floor form, a form pan consisting of a metal sheet having the longitudinal edges thereof bent to form side portions one of which has its edge further outwardly bent to form a laterally extending portion; and a flange formed upon the outer edge of the lateral extending portion to interlap with a side portion of an adjacent pan to form a mold for floor joist.

11. In a concrete form, a form pan consisting of a metal sheet having the longitudinal edges thereof bent to form side portion one of which has its edge further outwardly bent to form a laterally extending portion substantially parallel to the sheet, said side portions flaring outwardly slightly from perpendicular relation to said sheet; and an upwardly turned flange formed upon the edge of the laterally extending portion to interlap with the adjacent edge of an adjacent pan to form a mold for floor joist.

In witness whereof I hereunto set my signature.

RAYMOND C. PHELPS.
